UNITED STATES PATENT OFFICE.

ABNER DOBLE, OF DETROIT, MICHIGAN, ASSIGNOR TO DOBLE-DETROIT STEAM MOTORS CO., OF DETROIT, MICHIGAN, A CORPORATION OF DELAWARE.

STEAM-GENERATOR REGULATION.

Application filed May 9, 1918. Serial No. 233,486.

My invention has special reference to apparatus for generating steam, and is directed more particularly to improvements for regulating the fluid fuel and the water or other liquid employed for flash or semi-flash type of generators which have the capacity of superheating the steam which they generate and in which the temperature and the pressure of the steam at the point where it is discharged from the generator bear no uniform relationship to each other. That is, the steam pressure in such a generator may be anything from approximately zero up to the capacity of the generator, while the temperature of the steam at the delivery point may be substantially that of the steam table of the then existing pressure or anything above it.

The object of the invention is to automatically control the generation and heating of the steam to the end that the generator may automatically generate and prepare steam for delivery to an engine at substantially uniform pressure and at such temperature that what may be called the "ideal" conditions with respect to its temperature and pressure may obtain, and to accomplish this result regardless of the varying demands upon the generator for steam.

The ultimate object is to provide a steam generator and a system of controls for supplying an engine adapted to be safely operated by persons relatively unskilled in the use of machinery which will automatically and with the maximum of economy of water and fuel prepare for delivery to the engine an adequate supply of steam at such pressure and temperature to effect the most economical and efficient conditions. Such generators are of the greatest utility under steam automobiles which are commonly operated by relatively unskilled persons and whereon the supply of both water and fuel are necessarily very limited.

Another object is to provide an apparatus of the character referred to which is automatic in its operation and easily controlled, and which at the same time is safe and reliable and efficient even in the hands of careless or inexperienced operators, and which may be put into active condition without delay, and which when in action will almost instantly and with quick precision adjust itself to meet the greatly varying loads or demands upon it, and also simplify and

improve the apparatus whereby steam at a safe temperature and proper pressure may be supplied in situations where the demand for power varies greatly and the variations are sudden and irregular. This result is obtained by combining with a flash type of generator, two regulating devices each controlling the supply of the water and combustible, which by their consumption co-act to produce the desired result, and are so supplied, however much or in whatever particular the condition of the steam with respect to its temperature or pressure, or both, may have been temporarily varied from the ideal condition.

By reason of the fact that under some conditions which arise in use, a supply of either water or combustible must be provided, and concurrently the supply of one or the other must be interrupted, these regulating devices do not necessarily operate simultaneously or relatively in the same direction at all times. They would utterly fail to accomplish the desired result if they did necessarily always so operate, as under other circumstances both water and combustible must be supplied simultaneously, and under still other circumstances the supply of both must be diminished or interrupted simultaneously. The regulating devices do, however, act interdependently through the generator and the steam therein to automatically supply or interrupt a supply of water to the generator, or combustible to the heating device, or of both, as the then existing conditions require, whereby the water and heat are supplied in a manner to bring about the desired result,—that is, the maintenance so far as possible of the proper temperature and pressure of the steam in the generator or the speedy restoration of the steam therein to its ideal condition with respect to such temperature and pressure.

My invention, therefore, consists broadly in the combination with a steam generator provided with a liquid fuel burning device for heating the generator, and liquid forcing means for supplying water to the generator, and regulating devices responsive to the pressure of the steam, and also to its temperature, whereby the heating device and the water supplying device are under the control of both the said pressure and temperature actuated regulators in response to both the rise and fall of generator pressure.

and the rise and fall of generator temperatures.

My invention also consists in the more specific combination of parts which will 5 hereinafter more particularly appear in connection with the illustration and description of one form of specific embodiment of my invention.

Having reference to the accompanying 10 drawings:—

Figure 1 is a diagrammatic view illustrating a steam power plant especially adapted to a self-propelled vehicle, in which is diagrammatically disclosed the generator or 15 boiler, the liquid fuel burning device, the engine, the water pumps or liquid forcing means, and also illustrating the electric circuits and mechanism for controlling and regulating the water pumps, and also the 20 circuit arrangement and switches for controlling the heating device.

Fig. 2 is a top plan view of the generator or boiler, illustrating the relative position of the thermostatic mechanism for controlling 25 the water pumps and the heating devices, the thermostatic element of which is partially broken away to illustrate the interior construction thereof.

Fig. 3 is an enlarged front elevation illustrating the mechanism for operating 30 switches which control the circuits.

Fig. 4 is a vertical section thereof taken on the line 4—4 of Fig. 3.

Fig. 5 is a vertical section taken on the 35 line 5—5 of Fig. 3.

Fig. 6 is a horizontal section taken on the line 6—6 of Fig. 3.

While some of the advantages of my invention may be realized by the use of various 40 types of generators in connection with the regulating devices constructed in accordance with my invention, the best results can be obtained by the use of a generator or boiler of the flash type.

It has been determined that the quickest 45 acting method of maintaining a normal steam pressure is to control the fire directly by the steam pressure, and the most direct method of approximating a steam temperature 50 condition is to supply water when the fire is on and to interrupt the water supply when the fire is off. I have, therefore, provided water supply controls actuated by the steam-pressure-controller-firing means 55 whereby the variations of temperature from normal are corrected by a thermostat actuated control which determines that—below 600° F., or normal temperature, the water pumps shall remain inoperative, even 60 though the fire is on, and that between 600° F. and 700° F. one pump shall feed to the boiler when the fire is on, and that between 700° F. and 800° F. both pumps will feed the boiler when the fire is on, and at 800° 65 F. the fire is shut off by the thermostat with

both pumps still feeding the boiler. While the supply of fire and water are thus caused to respond to varying conditions of steam temperature, the control of both is immediately taken over by the steam-pressure-actuated control at a predetermined rise in steam pressure.

Having reference to the drawings, in which I illustrate the preferred form of my invention, A represents the boiler or steam generator which may be of any approved design, but is here shown as provided with the fire or combustion chamber A² located above the coils A³, the water being fed into the bottom coil as at A⁴, and is forced up 80 through the coils which gradually increase in diameter until it reaches the upper larger coils R², where it is flashed into steam, the steam being taken off through the pipe A⁵ and conveyed to the engine.

The liquid fuel is sprayed into the combustion chamber A² by the blower B, which is operated by the motor C, supplied with current from the generator D or battery E. The generator may be driven directly from the engine F, which engine may be of any approved type and is diagrammatically here shown as consisting of the steam cylinder F¹ and the crankcase F². Properly secured to the side of the crankcase are the water pumps G and H. These pumps being duplicates of each other, a description of one will suffice for the other. They are operated by a common plunger F³ reciprocated by an eccentric F⁴, mounted upon the crank-shaft 90 F⁵ of the engine F. The check-valve 10 of each pump is held off its seat by the spring 11, bearing against the movable core 12 of the solenoid 13, which core 12 is in contact by a rod 14 with the valve 10. When, however, the solenoid 12 is energized in a manner to be hereinafter described, the core 12 thereof is drawn downwardly into the solenoid, pressing the spring 11 so that the rod 14 permits the check-valve 10 to seat itself 100 and function in the usual manner.

Properly secured to the outer side of the boiler casing, near the upper end thereof, is the control box J, in which are mounted the electric switches operating in response to the 115 thermostatically-controlled and pressure-controlled regulators. Passing through the side of the box J, about midway its height, and rigidly secured thereto, is the pin J¹. Mounted to freely revolve about the pin J¹, which 120 passes through its short sides, is the hollow rectangular-shaped actuator yoke K, and mounted on this same pin within the hollow of the yoke K are the four movable contacts or switch arms L, M, N and O, capable of 125 oscillating about the pin J¹, through their hubs L¹, M¹, N¹ and O¹. Located in the lower portion of the box J, and formed integrally therewith, is the cylinder P constituting the casing of the pressure-actuated- 130

control mechanism. This cylinder is provided with the head P^1 securely bolted thereto by the bolts P^2 , which also secures the diaphragm P^3 in place by clamping it at its periphery between the head and the cylinder. The head is also provided with the steam opening P^4 . Secured to the piston rod P^5 , and resting on the upper side of the diaphragm is the piston head P^6 capable of a limited vertical movement. This piston is normally held against the diaphragm by the spring P^7 with a pressure as determined by the adjustment nut P^8 . In practice, it would be adjusted to resist a steam pressure of 600 pounds. A steam pressure in excess of this amount will force the diaphragm upwardly, causing the piston P^6 to contact the arm P^9 which is integral with the switch arm L , forming a bell crank therewith, pivoting on the pin J^1 . It will thus be seen that a slight upward movement of the piston will tilt the arm L about the pin J^1 in opposition to the retaining spring L^2 , extending from the arm to the rear wall of the box J . The extent of movement of the arm is determined by the adjusting screw L^3 which passes through the arm P^9 , bearing against the upper end of the piston P^6 . It will be observed from this description of the pressure-actuated control that it is entirely independent of and in no manner affected by the actuator K .

A thermostat comprising the brass tube R enclosing the steel rod R^1 is rigidly secured at one end inside the top coil R^2 of the boiler A , as more clearly shown in Figure 2. The free end of the tube R is free to expand longitudinally of the coil R^2 , and as the rod R^1 is rigidly secured to the inside of the free end of the tube, the outer end of the rod, which is extended out beyond the boiler casting and into the control box J , will have a withdrawing or receding movement corresponding to the longitudinal expansion of the tube R , the rod being made of an alloy having a comparatively low co-efficient of expansion. This rod is of a length that when cold its free end will bear against the lower horizontal member of the actuator K with sufficient force to hold the actuator in a practically vertical position in opposition to the compression spring R^3 bearing against the upper horizontal member of the actuator K and on the same side as does the rod R^1 . It will thus be seen that upon a receding of the rod through expansion of the tube R , the actuator will be given a rotating movement about the pin J^1 in response to the compression spring R^3 . It is this rotating or oscillating movement of the actuator K upon the pin J^1 that is utilized to operate the various electric circuits in connection with thermostatically controlled water and fuel supply regulating means.

As more clearly shown in the diagrammatic layout (Fig. 1), the switch arm L , controlled by the pressure-actuated regulator through the piston P^6 , extension P^9 , and adjusting screw L^3 is normally held in contact with the stationary contact or pole piece S by the retaining spring L^2 , and the switch arm M is normally held in contact with the pole piece S^1 , by the retaining spring M^2 . This arm is provided with an adjusting screw M^3 , which can be so adjusted relative to the actuator K that upon a given forward rotating movement of the actuator in response to the receding of the thermostatic rod R as influenced by the boiler temperature, contact between the arm M and the pole piece S^1 will be broken. Likewise, switch arms N and O are provided with the adjusting screws N^3 and O^3 , which can be adjusted relative to the actuator K in opposition to the retaining springs N^2 and O^2 to prevent contact of the arms with the stationary contacts or pole pieces S^2 and S^3 . In practice, one of these arms will be adjusted in a manner to be held from the pole piece a distance slightly in excess of the distance that the other arm is held away from its stationary contact.

The pressure actuated switch L , which, as hereinbefore stated, is normally held closed by its retaining spring L^2 , is connected to a source of current supply through the lead 15, which circuit is adapted to be opened by the pressure-controlled regulator responsive to steam pressure in the boiler. This main circuit is also adapted to be closed by the manually-operated switch T . A lead 16 from the switch L is divided into three branches 17, 18 and 19. The branch 17 extending to the motor C through the medium of the switch M , which switch is also normally held closed by its retaining spring M^2 , and adapted to be opened by the actuator K through the receding of the rod R^1 in response to a predetermined degree of rise of steam temperature. The branches 18 and 19 extend respectively to the switch arms N and O . These switches are normally held open through the medium of the adjusting nuts N^3 and O^3 bearing against the actuator K , and adapted to be closed upon the receding of the thermostatic rod R^1 in response to a predetermined degree of rise in the steam temperature. A lead 20 extends from the stationary contact S^1 associated with the switch M to the motor C which drives the blower B , constituting the fuel supply means. This lead 20 is passed through the automatic fuel and ignition control V on its way to the motor C . This liquid fuel burning device, including the automatic control and the ignition thereof, forms the subject-matter of a co-pending application Serial Number 178,513, filed July 3, 1917, upon which Patent 1,287,915 was granted December 17, 1918. I will herein describe this part of the mechanism only sufficiently to 130

show its cooperation with the other parts of the structure, and before doing so will complete the description of the construction and operation of the other parts of the apparatus.

A lead 21 extends from the stationary contact S^2 associated with the switch N to the solenoid 13 of pump G, and the lead 22 extends from the contact S^3 associated with switch O to the solenoid of pump H. The water is drawn from the tank 25 through the suction pipe 26 and discharged through the pipe 27, compensator 28 and pipe 29 to the boiler at A⁴.

13 The operation of my improved automatic controls, as applied, by way of illustration, to a steam-driven vehicle, is as follows: On closing the manually-operated switch T, which is conveniently located at the steering 20 wheel, current is supplied from the battery through the leads 15, 16, 17 and 20 to the motor C through the automatic fuel and ignition control apparatus V, immediately filling the combustion box A² with a voluminous flame from the burning spray of liquid fuel blown therein by the blower and automatically ignited by an electric spark. With the fire thus started and the boiler nearly full of water, the pressure and steam 25 temperature build up, the car is then put under headway, and if the demand for steam is normal as a result of running at normal speed on good roads, no more water will be supplied until the temperature rises to about 600°, when the thermostatic rod R¹ will recede sufficiently to permit the compression spring R³ to force the upper portion of the actuator K forwardly and the lower portion rearwardly to a point where- 30 by the retaining spring N² will draw the switch arm N into contact with the stationary contact S^2 , closing the circuit to the solenoid 13 in connection with pump G, releasing check-valve 10, enabling it to function in the usual manner, whereby the water drawn through the pipe 26 will be forced to the boiler coils through pipe 27, compensator 28 and pipe 29. It is, of course, understood that with the pumps running and the 35 solenoid de-energized, the spring 11 will force the check-valve 10 off its seat, permitting the water to surge back and forth, none going to the boiler.

If the demand for steam increases as a 40 result of climbing a steep grade or a long pull through heavy sand or mud, the temperature will continue to rise, and on reaching about 700° there will have been a sufficient movement of the actuator K through 45 a continued receding of the thermostatic rod R¹ to close the circuit at S^3 , whereby the solenoid in connection with pump H is energized, and both pumps will then operate to feed water to the boiler coils. 50

65 With the fire thus burning to its maximum

and both pumps feeding water to supply steam to the maximum capacity of the boiler, the summit of the hill is passed, and the car is coasting down the hill, thus bringing about a sudden cessation of demand for steam through the closing of the throttle, the pressure will naturally and suddenly rise to an abnormal degree, but, as will readily be seen, the pressure-actuated switch L, which when the pressure reaches a predetermined amount (in practice 600 pounds), will take over the control of the supply of both fire and water by opening the main circuit at a point in advance of the thermostatically-operated switch M, and thus shut down the entire system. The pressure-actuated regulator, operating independently of the thermostatically-operated regulators, is, therefore, capable of and is often called upon to take over control of both fire and water, regardless of temperature conditions. A continued rise of temperature, which may be predetermined at about 800°, will bring the upper part of the actuator K in contact with the adjusting nut M³ 55 of the switch-arm M, breaking the circuit at S¹, and thus also cut off the fire by stopping the blower B. An abnormal rise of temperature is thus prevented—not only by a timely discontinuance of the fire, but also 60 by reason of the fact that both pumps will still continue to feed water to the boiler, and they will so continue to feed until the temperature has again reached normal. Thus it is that in starting the car, it is only 65 necessary to turn on the fire, the pressure and temperature build up until the fire is shut off by either high condition of pressure (600 lbs.) or of temperature (800°), depending upon whether the boiler is nearly 70 full or nearly empty of water. If the car is started with the boiler nearly full, no more water is applied until 600° is reached. If nearly empty, water is supplied at the maximum capacity until the temperature is reduced. In the first case, the fire is controlled 75 at 600 pounds pressure at all times; in the second case, the fire is controlled by 800° temperature until the steam pressure rises to 600 pounds, when it then takes over the 80 fire and water control.

From the foregoing description, it is apparent that I have provided means for bringing into operation a plurality of pumps—one after the other—and finally cutting off the fuel supply while the two pumps continue to operate and feed water to the generator coils, thus bringing about a condition which exerts a maximum effect in the reduction of the temperature. If the temperature rises suddenly to a degree beyond which if it still further increased, would be abnormal, the two pumps are immediately brought into action, and the fuel supply cut off. If, on the other hand, the rise of 120

125

130

- temperature is gradual, under which conditions a minimum quantity of water should be supplied by the generator, then only one of the two pumps is brought into action, and thus the generation of the steam is not checked by supplying too great a quantity of water to the generator, or by the cutting off of the fuel supply. As the temperature still rises, requiring that more water should be supplied to the generator coils, the second pump is brought into action, and only upon a rise of temperature, which if persisted in, would be abnormal, is the fuel supply cut off. It is further evident that if for any reason the first pump failed to operate and supply water to the generator, as there would be an increase in temperature, the second pump is then brought into operation, and if its supply of water is not sufficient and the temperature rises to an abnormal point, then the main circuit is opened, cutting off the fuel supply; and it is further evident that if the second pump fails to operate, the first pump operating would supply water to the generator, and under such conditions if the temperature rises to an abnormal degree, the fuel supply is then cut off. So, also, if neither pump, for any cause, operates to supply water to the generator when demanded, the temperature then rising to an abnormal point, the circuit is opened and the fuel supply and the main circuit cut off, and if for any reason the pressure should build up abnormally, regardless of boiler temperature, the supply of both fuel and water is immediately taken over by the pressure actuated regulator.
- The ignition and fuel control mechanism, designated generally by the letter V is interposed in the conductor 20 between the thermostatic and pressure control mechanism and the blower motor C. The fuel control mechanism comprises a vessel X designed to contain a charge of compressed air sufficient to operate the ignition burner. The air from the blower B is delivered direct to the Venturi tube b² of the main burner which communicates with the combustion space A² at the top of the boiler. Adjacent the main burner is an ignition burner b⁶. Both the main burner and the ignition burner receive liquid fuel from the tank c. A hand-operated pump c¹ and an engine-operated pump c² are provided for maintaining air pressure in the tank c, and a float-valve regulator d⁴ serves to maintain the liquid fuel at the proper level in the oil nozzles b³ and d² of the main and ignition burners respectively.
- The lower end of the air tank X is provided with an opening controlled by valve c¹⁰ formed on the lower end of valve stem c¹¹, and a pipe c⁹ extends from the valve controlled opening to the ignition burner as shown in Fig. 1. At its upper end the stem c¹¹ takes the form of a valve c¹² which controls communication between the interior of vessel X and a port which is connected by a pipe e³ with the compressed air space above the liquid fuel in tank c. A solenoid g' is fixedly mounted in the lower part of tank X and the core g of the solenoid is fixed to the valve stem c¹¹. A spring g⁵ seated at its upper end against a part of the stationary spool or fixed core of the solenoid and at its lower end against the movable core g serves when the solenoid is de-energized to depress stem c¹¹ thus closing valve c¹⁰ and opening valve c¹², and energization of the solenoid raises stem c¹¹ opening valve c¹⁰ and closing valve c¹². Communicating with the port leading from valve c¹² to air-pressure pipe e³ is an outwardly opening cup-shaped casting closed by a flexible diaphragm e⁵. An electrical terminal e⁸ is stationarily supported upon a bridge e⁷ outside of the diaphragm and in position to be in contact with the diaphragm when the latter is forced outward by air-pressure. The terminal e⁸ is insulated and the diaphragm serves to ground the terminal when in contact therewith. It will be noted that the inner side of diaphragm e⁵ is constantly subjected to the pressure of the air in fuel tank c. A diaphragm t and terminal t² similar to diaphragm e⁵ and terminal e⁸ is also provided, the space inside of diaphragm t being in direct and constant communication with the interior of tank X. Fixedly mounted on stem c¹¹ and insulated therefrom is an electrical switch member 1 which serves when stem c¹¹ is elevated by the energization of solenoid g' to establish contact between terminals 1', 1', which are mounted within the tank X.
- The main conductor 20 leading from the terminal s' of the thermostatic and pressure control is connected to one of the terminals 1' and the other terminal 1' is connected by conductor p² to the blower motor c. A branch g⁷ of conductor 20 extends to one terminal of solenoid g' and the other terminal of the solenoid is connected by conductor g⁸ to terminal e⁸, and a branch conductor t⁵ extends from branch conductor g⁷ through the primary of spark coil t⁴ to terminal t². The secondary of spark coil t⁴ has one terminal grounded and the other connected to spark plug e which is mounted on the ignition burner in the path of the sprayed oil therein.
- The main burner b² hereinbefore described produces a mixture of atomized fuel and air which is completely combustible and which burns in the combustion chamber without any smoke or soot whatever. But a mixture of this character which is supplied with sufficient air to be completely combustible, will not ignite directly from a spark of practical proportions. I do find in practice, however,

that a mixture which is very rich in hydro-carbon, although incompletely combustible because of insufficient air, will very readily and repeatedly ignite at normal temperature 5 by means of an electric spark, and the advantage of this is that it is instantaneous.

The ignition burner b^6 is provided with a curved lip b' , so as to direct the flame from the auxiliary mixture into the path of the 10 main mixture to directly and instantaneously ignite said main mixture.

The ignition burner is so designed and operated as to produce a mixture of such richness as to be readily ignitable by the 15 spark plug e .

When the engine is at rest with the main electrical circuit open at the driver's switch T or at the thermostatic and pressure control switch, designated generally 100, solenoid 20 g' of the fuel and ignition control is de-energized and valve c^{10} is held seated by spring g^5 thus preventing flow of air through pipe c^9 to burner b^6 , and the constant air pressure on the inner side of dia- 25 phragm e^5 maintains electrical connection from main conductor 20 through g^7 , solenoid g' , g^8 terminal e^8 , diaphragm e^5 and the metal structure to ground at 200. When the main circuit through conductor 20 is closed 30 both at T and at 100 current flows from 20 through the solenoid g' , diaphragm switch e^8, e^5 , to ground as above stated. The resulting energization of solenoid g' acting upon the core g attached to the stem c^{11} and valves 35 c^{10} raises the valve against the tension of spring g^5 and at the same time closes the valve c^{12} at the upper end of the stem c^{11} . The charge of air so entrapped in X is delivered through pipe c^8 to the ignition-starting 40 burner b^6 , thus spraying oil from b^3 which leads from float chamber d^4 . The air pressure in X also closes the diaphragm switch t, t^2 , and permits current to flow from g^7 through t^5 , primary of spark coil t^4 and dia- 45 phragm switch t^2, t , to ground. Lead e' leads from the secondary of the spark coil to spark plug e . When c^{11} is raised by the solenoid as above described, it carries up with it switch member l which is attached to stem 50 c^{11} and electrical connection is thereby established between terminals l' and l' thus closing the circuit from main conductor 20 to blower motor C . The blower, therefore, starts the spraying of oil into the main 55 burner b^2 simultaneously with the actuation of the ignition starting operation in the starter burner b^6 , and the main flame is thereby started. When the air entrapped in X has become exhausted the fall of pressure 60 therein causes the diaphragm switch t, t^2 to open and discontinue current through spark coil t^4 . Throughout the operation of the main burner valve stem c^{11} remains elevated. When the main circuit is opened, 65 either by the operator opening switch T ,

or by the automatic operation of the thermostatic and pressure control 100, solenoid g' is de-energized, valve stem c^{11} is depressed by spring g^5 , a new supply of air pressure flows to X through valve c^{12} , diaphragm 70 valve t, t^2 , is closed and the main circuit is opened between terminals l', l' . Everything is now again in readiness for the starting cycle above described.

The flow of oil to the burner except when 75 there is a supply of compressed air to operate the ignition nozzle is prevented by the opening of the circuit of solenoid g' at the diaphragm switch e^6, e^8 , whenever the air pressure falls below a predetermined point. 80 It is only when the solenoid circuit is closed that terminals l', l' , are connected by bridge l . Hence failure of air pressure to operate the ignition device prevents operation of the blower motor.

What I claim as my invention is:

1. In a system for the control and regulation of steam for a steam power plant, means for initiating a supply of water to the generator upon attainment of a predetermined degree of steam temperature, and means for increasing the water supply upon attainment of a still higher predetermined degree of steam temperature.

2. In a system for the control and regulation of steam for a steam power plant, a plurality of feeding devices for supplying water to the generator, means for initiating the operation of one of the feeding devices upon attainment of a predetermined degree of steam temperature, and means for initiating the operation of another water feeding device upon attainment of a still higher predetermined degree of steam temperature.

3. In a system for the control and regulation of steam for a steam power plant, liquid fuel feeding mechanism and means for controlling the same, a plurality of feeding devices for supplying water to the generator, means for initiating a supply of water upon attainment of a predetermined degree of steam temperature, and means for increasing the water supply upon attainment of a still higher predetermined degree of steam temperature, together with means for actuating the fuel feed control to stop the supply of liquid fuel and permit the continued operation of the means for supplying water.

4. In a regulator for steam boilers, the combination of a steam generator, a thermostatic fuel and water regulator responding to the temperature of the steam in the generator, a liquid fuel burning device controlled by said thermostatic regulator, liquid forcing means for supplying vaporizable liquid to the generator, a steam pressure fuel and water regulator responding to the pressure of the steam in the generator, and oper-

85

100

105

110

115

120

125

130

- atively connected to the liquid fuel burning device for controlling its operation and operatively related to said liquid forcing means for automatically discontinuing the vaporizable liquid supply and liquid fuel supply upon a predetermined rise in the generator pressure.
5. A system for the control and regulation of the generation of steam for a steam power plant, consisting of a plurality of feeding devices for supplying water to the generator, electromagnetically-operated means for initiating the operation of one or more of said feeding devices, and thermostatically-operated means responsive to variations in generator conditions which control the operation of the electromagnetically-operated means.
6. A system for the control and regulation of steam for a steam power plant, consisting of a plurality of feeding devices for supplying water to the generator, a source of fuel supply, means for feeding the fuel to a combustion chamber, an actuator, a 25 thermostat, responsive to temperature variations of a generator, for controlling the actuator, means connecting the actuator with each one of the plurality of water feeding devices whereby to bring the same into operation, and means operated by the actuator to cut off the fuel supply when the temperature is above that necessary to initiate the operation of all of the water feeding devices.
- 35 7. A system for the control and regulation of the generation of steam for a steam power plant, consisting of a plurality of feeding devices for supplying water to the generator, electromagnetically-operated means for initiating the operation of one or more of the feeding devices, thermostatically-operated means responsive to variations in generator conditions which control the operation of the electro-magnetically-operated means, a source of fuel supply, and mechanism for supplying fuel to a combustion chamber, together with thermostatically controlled means also responsive to variations in generator conditions for automatically cutting off the fuel supply when the temperature is above that necessary to initiate the operation of all of the water feed devices.
8. A system for the control and regulation of the generation of steam for a steam power plant, consisting of a plurality of feeding devices for supplying water to the generator, electromagnetically-operated means for initiating the operation of one or more of the feeding devices, comprising a solenoid adapted to bring into operation the feeding devices, thermostatically-operated means responsive to variations in generator conditions which condition the operation of the electromagnetically-operated means, a source of fuel supply, and mechanism for supplying fuel to a combustion chamber, together with thermostatically-controlling means also responsive to variations in generator conditions for automatically cutting off the fuel supply when the temperature is above that necessary to condition the operation of all of the water feed devices.
9. In a control for a steam generator plant, a plurality of pumps for feeding water to the generator inoperative at a certain definite temperature, means operated by the rise of temperature which causes one of said pumps to become operative upon a certain rise in temperature, means which cause the other pump to become operative upon further rise of temperature, a source of fuel supply and means for cutting off the fuel supply upon further rise of temperature.
10. A system for controlling the generation of steam in a steam generator system, consisting of an actuator, a thermostat for controlling the actuator, a plurality of water-feeding devices, electromagnetically-operated means for initiating the action of the feeding devices, a circuit for each of said electromagnetically-operated devices, said circuits including switches controlled by said actuator, electrically-controlled means for supplying fuel, and a circuit for said electrically-controlled means including a switch operated by the actuator to operate the electrically-controlled means for supplying fuel, whereby the fuel supply is cut off.
11. In a regulator for steam boilers, the combination of a steam generator, a steam-pressure-actuated regulator responsive to the pressure of the steam in the generator, a thermostatic regulator responsive to the temperature of the steam in the generator, a liquid-fuel burning device for heating the steam generator, a liquid forcing means for supplying water or other vaporizable liquid to said steam generator, both said device and said means arranged to be operatively dependent upon said pressure and said temperature actuated regulators in response to the rise and fall of steam pressure, as well as the rise and fall of steam temperature.
12. In a regulator for steam boilers, the combination of a steam generator, a liquid fuel burning device for heating the same, a liquid forcing means for supplying vaporizable liquid to said generator, a thermostatic regulator responsive to the temperature of the vapor in said generator, a steam pressure actuated regulator responsive to the pressure of said vapor, said thermostatic regulator adapted to actuate the said liquid forcing means and discontinue the action of the said liquid fuel burning device in response to a successive predetermined rise in vapor temperature, and said steam-pressure-actuated regulator adapted to also control

the liquid forcing means and the liquid fuel burning device, whereby the operation of both are automatically responsive to a pre-determined rise and fall in steam pressure.

- 5 13. In a steam boiler regulator, the combination of a steam generator, a liquid-fuel burning device for heating the same, a liquid forcing means for supplying vaporizable liquid to the generator, means responsive to 10 generator conditions to simultaneously render said liquid-fuel-burning device and said liquid-forcing means inoperative, and means which permit a continuance of the operation of said liquid-forcing means to supply water 15 after the said liquid-fuel-burning device is rendered inoperative.
14. In a regulator for steam boilers, the combination of a steam generator, a thermostatic fuel regulator responsive to the temperature of the steam in the generator, a liquid fuel burning device having its fuel supply controlled by said thermostatic regulator, a steam pressure controlled regulator 20 responsive to the pressure of the steam of the generator and operatively related to the liq- 25

uid fuel burning device also for controlling the fuel supply thereof, a liquid forcing means for supplying vaporizable liquid to the generator operatively related to said thermostatic regulator and controlled by said pressure-controlled regulator for automatically discontinuing the vaporizable liquid supply upon a predetermined rise in the generator pressure.

- 30 15. In a regulator for steam boilers, the combination of a steam generator, a liquid fuel burning device for heating the same, a liquid forcing means for supplying water or other vaporizable liquid to said generator, a generator-pressure-actuated regulator for controlling the fuel to said liquid-fuel burning device, and the vaporizable liquid to said generator, and a generator-temperature-actuated regulator for also controlling the fuel to said fuel burning device and the 40 said vaporizable liquid to said generator.

45 Signed by me at Detroit, Michigan, this 9th day of March 1918.

ABNER DOBLE.
